UNITED STATES PATENT OFFICE.

WILLIAM H. HART, JR., OF PHILADELPHIA, PENNSYLVANIA.

DESIGN FOR A BICYCLE-SUPPORT.

SPECIFICATION forming part of Design No. 31,479, dated August 29, 1899.

Application filed August 3, 1899. Serial No. 726,052. Term of patent 7 years.

To all whom it may concern:

Be it known that I, WILLIAM H. HART, JR., a citizen of the United States, residing in the city and county of Philadelphia, State of Pennsylvania, have invented and produced a new and original Design for a Bicycle-Support, of which the following is a specification, reference being had to the accompanying drawings, forming part thereof.

The leading feature of my design for a bicycle-support is a standard of elbow form and a limb on the upper end thereof.

Figure 1 represents a perspective view of a bicycle-support embodying my design. Fig. 2 represents a side elevation thereof.

In the drawings, A designates a standard consisting of the side pieces B, with elbows C in the direction of their length. At the upper ends of the standards are laterally-projecting limbs D. The lower ends of the standards are connected by the base E.

Having thus described my invention, what I claim as new, and desire to secure by Letters Patent, is—

The design for a bicycle-support substantially as shown and described.

WILLIAM H. HART, JR.
